CATHODE RAY TUBE

Kurt Schlesinger, Berlin, Germany, assignor to
 Radioaktiengesellschaft D. S. Loewe, Berlin-
 Steglitz, Germany, a company of Germany

Application November 5, 1938, Serial No. 239,154
 In Germany April 5, 1938

9 Claims. (Cl. 250—162)

The invention relates to improvements in the electron-optical arrangement, more particularly for Braun tubes of high output, in which a diaphragm aperture acts as object of reproduction 5 and a so-called intersection-point optical system is employed.

It has already been proposed by the applicants on a previous occasion to use large-surface cathodes in conjunction with a net-like control grid, in order in this way considerably to increase the properly controllable intensity of the ray current. The realisation of this idea is confronted by difficulties in the electron-optical treatment of the electronic ray. It has been observed that the image point on the screen has always been considerably larger than was to be expected on the basis of the simple laws of electron-optical reproduction which have been employed heretofore and up to now have been 10 found to be sufficiently accurate. The reason for this difference is due only in part to the nature of the electron-optical system employed, which theoretically can be controlled only with difficulty. For the other part, as experiments have 15 conclusively shown, it must be laid down to errors of reproduction on the part of the electronic lenses. Generally speaking, the main lens is incapable of uniting in the same point as the rays which are near to the axis the rays which 20 are remote from the axis and the direction of which forms with the axis a comparatively large angle. In consequence there is a deformation and an increase in the size of the image point, which in unfavourable circumstances may even 25 go so far that subsidiary images are produced, i. e., that in place of one image point several of these appear on the screen. The reason for 30 this latter effect has been found to consist in the fact that the preliminary concentration system is incapable of handling marginal rays which 35 form an excessively large angle with the axis. Further, there are frequently observed appreciable halo effects, which are due to the 40 considerable formation of secondary electrons at the 45 edge of the diaphragm in the case of great intensity of the ray current. It is the object of the invention to eliminate the image errors referred to.

The electron-optical arrangement according to 50 the invention is illustrated diagrammatically by way of example in Fig. 1. The preliminary concentration system, which unites in the aperture of the diaphragm acting as object of reproduction all rays which pass through the control grid, 55 is formed by the diaphragm 1, the aperture-lens

electrode 7 and the cathode 6. According to the invention, there is provided in front of the diaphragm 1 an electrode 8 which is raised to the same potential as the diaphragm and is preferably united by means of an annular intermediate 5 member with the diaphragm itself to form a single metallic diaphragm element. The inlet aperture α of the diaphragm element determines in conjunction with the spacing c between the electrodes 8 and 1 the angle of entry α of the 10 ray into the diaphragm, or into the lens space situated behind the same, and serves to shade off interfering, excessively inclined marginal rays. The aperture electrode 1 may not be employed as diaphragm, as otherwise marginal 15 errors will again unavoidably occur. Its opening must always be somewhat larger than the cross-section of the electronic ray traversing the same.

In order as far as possible to render harmless the heat developed by impact of the electrons 20 the diaphragm 1 is formed by a thick metallic disc having a conical recess at its centre. The actual diaphragm aperture is located in a thin sheet of platinum, which is welded on to the rear of the metallic ring. 25

According to the invention, the main lens consists of an inlet tube 2, which has a lower potential than the diaphragm, and an outlet tube 3, which is raised to anode potential and is preferably metallically connected with the anode 4. 30 At the same time, according to the invention, the diameter of the outlet tube is selected to be approximately one-half of the diameter of the inlet tube. The outlet tube extends for approximately one-half of its length into the inlet tube. 35

According to an additional feature of the invention, there is introduced into the interior of the cylinder 2 a further perforated diaphragm 14, spaced to such extent from the lens field that interference with this field by the diaphragm 14 40 is out of the question, i. e., at a distance of at least 2-3 times o_1 . The size of the opening 14 is such that all rays passing through the same enter the main lens within an angle amounting to 80-90% of that determined by o_1 . In this 45 way rays which are extremely remote from the axis and cannot be properly embraced by the main lens are precluded. On the other hand the effect of the diaphragm 14 is obtained all the more readily the more it is spaced away 50 from the main diaphragm.

The connecting of the tube in accordance with the invention is particularly important. The anode 4 is connected with the highest positive potential, the tubular lens electrode 2 with a low 55

adjustable focussing potential. The bias of the diaphragm 1 can be adjusted as desired at the point 9 of a potentiometer.

In the case of variation of the diaphragm bias 5 there occurs the following: If the bias of the diaphragm 1 is increased until it gradually reaches the full anode potential, the energy in the image point is increased considerably with approximately constant density of energy, i. e., the 10 diameter of the image point also increases. Accordingly, by varying the tapping 9, the size of the image point, with constant and well defined form of the luminous spot, can be so adjusted that the lines just overlap. It is an attendant 15 feature of the arrangement as described that, without special means, a considerable fraction of the oncoming electronic current is swallowed up by the diaphragm itself. In consequence the bias of the diaphragm varies in a 20 manner dependent on the medium image current. These fluctuations in the potential of the diaphragm, however, do not make themselves noticeable in the form of impaired sharpness of the image point, but only as a practically negligible 25 variation in its size. Smoothing means for the diaphragm can accordingly be dispensed with.

Owing to the varying current reception on the 30 part of the diaphragm 1, however, there also varies at the same time the bias of the lens electrode 2. Each variation in the potential of this electrode, however, makes itself immediately noticeable by lack of sharpness of the image. Care must accordingly be taken that potential 35 fluctuations of the tube 2 are prevented.

Tests have shown that the cylinder 2 remains practically free from current reception entirely 40 so long as the bias of the diaphragm element 1/8 is positive in relation to the bias of the cylinder. There results from this a simple method of maintaining the potential of the electrode 2 constant during the operation of the tube. According to the invention, smoothing elements 45 10/11 are connected in the lead to the electrode 2. At the same time the time constant of this combination must be greater than the image change period in order to avoid that the sharpness of the point is affected by the contents of the image. There can be employed a comparatively high 50 resistance 10 (approximately 0.5 to 1 megohm), and a comparatively small condenser 11 (approximately 0.1 μ F.) is then sufficient. It may be established at this point that against all expectations the smallest sharp image point capable 55 of being obtained at the screen 5 has the size resulting from the simple law of spacing, and that all image points which are obtained by increasing the bias of 1 beyond the bias of 2 are larger than this extreme value.

60 Of particular importance in the selection of the concentration system is the spacing a between control grid and electrode 7 and the spacing c between diaphragm 1 and electrode 8. As already shown above, the diaphragm element 8 65 determines the angle α at which the bundle of rays enters the tubular space after traversing the concentration field. There must accordingly be maintained approximately the proportion $o:c=o:l$, o being the size of aperture of the 70 outlet cylinder 3 and l the spacing 1, 4. The spacing a determines together with the quotient of the potentials at 7 and 8 the scale by which the cross-section of the ray is reduced from the cathode 6 up to the diaphragm 1. In this connection, if b is the spacing between 7 and 8, the 75

distance $b+c$ as image width is of a practically fixed nature. Experiments have shown the most favourable scale of reduction to have a value of approximately 5:1. Since experiments have also shown that the most favourable potential distribution for the electrodes of the concentration system is fixed within comparatively narrow limits, the said spacing a and also the greatest cathode surface capable of being utilised are by reason of the electron-optical law of reproduction 10 also of a definitely fixed kind.

According to an additional feature of the invention, the net electrode 15 acting as control grid is itself designed as diaphragm by the fact that its aperture is made equal to the cathode 15 surface capable of being utilised or only very little larger. In this manner there is prevented at the outset the occurrence of marginal rays which are so greatly inclined in relation to the axis that they could in no case be properly handled by the 20 concentration optical system.

The net should divide the cathode surface into at least 10, and preferably more, elementary areas. With a cathode diameter of 1.5 mm. and a grid constant of 0.5 mm. 9 grid windows can 25 be obtained.

Fig. 2 shows as an additional feature of the invention an arrangement with which it is possible to make the diaphragm 1 itself currentless, and at the same time to prevent a halo effect in 30 the vicinity of the image point caused by secondary electrons. In this case the diaphragm 1 preferably has the same potential as the tubular member 2, with which it can be metallically connected. On the inlet side of the cathode ray there is located a special aperture-electrode 13, which as compared with the diaphragm is raised to a potential which is positive to the extent of a few hundred volts. The spacing between 13 and 35 1 is preferably of the order of the aperture of 40 13. Both amount to approximately 1 mm. Immediately the electrode 13 has a potential which is at least 100 volts higher than the diaphragm 45 the diaphragm circuit is without current.

The explanation for this effect is to be found 45 in the secondary emission occurring at the edge of the diaphragm, for which emission in the case of potentials of more than 200 volts the ratio S:P is already greater than 1, and certainly, therefore, in the case of those potentials with 50 which cathode ray tubes are operated. The bias of the electrode 13 can accordingly be adjusted in such fashion that the loss current of the diaphragm is immediately again compensated by 55 secondary emission currents.

It has been found that the electrode 13 is capable of completely replacing in effect the electrode 8 in Fig. 1, so that the latter is superfluous.

A combination of this kind comprising a suctional electrode 13 and an aperture diaphragm 1 60 can be employed in all cases in which elimination of the current loss of the diaphragm is desired. The provision of the suctional electrode on the inlet side of the cathode ray has the advantage 65 that the secondary emission is absorbed before the secondary electrons enter the space of the main lens. In this way the image point is freed from its interfering halo.

What I claim as new and desire to secure by 70 Letters Patent is:

1. A cathode ray tube comprising means including a cathode for producing and controlling a cathode ray, a first apertured diaphragm, a concentrating electron optical system comprising two further diaphragms for focusing said cathode 75

ray in the aperture of said first diaphragm, an intensity control electrode arranged between said cathode and said concentrating system and consisting of a fine-wire net supported by another diaphragm, the aperture of which has approximately the same size as the emissive surface of said cathode, a luminescent screen, and a further electron optical system for reproducing the aperture of said first diaphragm on said screen, all 10 of said diaphragms having apertures the diameters of which decrease inversely proportional to the distance of said diaphragms from said control electrode, said second electron optical system comprising a first cylinder and a second cylinder mounted co-axially with said first cylinder and extending to the space between said first cylinder and said screen, said second cylinder having a diameter of approximately $\frac{1}{2}$ of the diameter of said first cylinder and extending into said first cylinder for approximately 20 $\frac{1}{2}$ of its length.

2. A cathode ray tube comprising means including a cathode for producing a cathode ray, an intensity control electrode mounted in front of the emissive surface of said cathode, a first apertured diaphragm, an electron optical preconcentrating system adapted to produce a first focus of said cathode ray in the aperture of said first diaphragm, said preconcentrating system consisting of said first diaphragm and two further apertured diaphragms mounted between said first diaphragm and said control electrode, the intermediate of said three diaphragms having a smaller distance from said first diaphragm than from the third of said diaphragms, the apertures of said three diaphragms having decreasing diameters in the direction from said cathode, the size of the aperture of said first diaphragm being approximately equal to one fifth of the size of the active emissive surface of said cathode.

3. A cathode ray tube comprising means including a cathode for producing a cathode ray, an intensity control electrode mounted in front of the emissive surface of said cathode, a first apertured diaphragm, an electron optical preconcentrating system adapted to produce a first focus of said cathode ray in the aperture of said first diaphragm, said preconcentrating system consisting of said first diaphragm and two further apertured diaphragms mounted between said first diaphragm and said control electrode, the intermediate of said three diaphragms having a smaller distance from said first diaphragm than from the third of said diaphragms and being electrically connected with said first diaphragm.

4. A cathode ray tube comprising means including a cathode for producing a cathode ray, an intensity control electrode mounted in front of the emissive surface of said cathode, a first apertured diaphragm, an electron optical preconcentrating system adapted to produce a first focus of said cathode ray in the aperture of said first diaphragm, said preconcentrating system consisting of said first diaphragm and two further apertured diaphragms mounted between said first diaphragm and said control electrode, the intermediate of said three diaphragms having a smaller distance from said first diaphragm than from the third of said diaphragms and being electrically connected with said first diaphragm, the apertures of said three diaphragms having decreasing diameters in the direction from said cathode, the size of the aperture of said first diaphragm being approximately equal to

one fifth of the size of the active emissive surface of said cathode.

5. A cathode ray tube comprising means including a cathode for producing a cathode ray, an intensity control electrode mounted in front of the emissive surface of said cathode, a first apertured diaphragm, an electron optical preconcentrating system adapted to produce a first focus of said cathode ray in the aperture of said first diaphragm, said preconcentrating system consisting of said first diaphragm and two further apertured diaphragms mounted between said first diaphragm and said control electrode, the intermediate of said three diaphragms having a smaller distance from said first diaphragm than from the third of said diaphragms, the apertures of said three diaphragms having decreasing diameters in the direction from said cathode, the size of the aperture of said first diaphragm being approximately equal to one fifth of the size of the active emissive surface of said cathode, said control electrode consisting of a fine-wire net supported by a further diaphragm the aperture of which has approximately the same size as the active emissive surface of said cathode.

6. A cathode ray tube comprising means including a cathode for producing a cathode ray, an intensity control electrode mounted in front of the emissive surface of said cathode, a first apertured diaphragm, an electron optical preconcentrating system adapted to produce a first focus of said cathode ray in the aperture of said first diaphragm, said preconcentrating system consisting of said first diaphragm and two further apertured diaphragms mounted between said first diaphragm and said control electrode, the intermediate of said three diaphragms having a smaller distance from said first diaphragm than from the third of said diaphragms, the apertures of said three diaphragms having diameters decreasing substantially inversely proportional to the distance of said diaphragms from said control electrode, the size of the aperture of said first diaphragm being approximately equal to one fifth of the size of the active emissive surface of said cathode.

7. A cathode ray tube comprising means including a cathode for producing a cathode ray, an intensity control electrode mounted in front of the emissive surface of said cathode, a first apertured diaphragm, an electron optical preconcentrating system adapted to produce a first focus of said cathode ray in the aperture of said first diaphragm, said preconcentrating system consisting of said first diaphragm and two further apertured diaphragms mounted between said first diaphragm and said control electrode, the intermediate of said three diaphragms having a smaller distance from said first diaphragm than from the third of said diaphragms, the apertures of said three diaphragms having diameters decreasing substantially inversely proportional to the distance of said diaphragms from said control electrode, said control electrode consisting of a further diaphragm having a central opening of approximately the same size as the active emissive surface of said cathode, the size of the aperture of said first diaphragm being approximately equal to one fifth of the size of the active emissive surface of said cathode.

8. A cathode ray tube comprising means including a cathode for producing a cathode ray, an intensity control electrode mounted in front of the emissive surface of said cathode, a first

5 apertured diaphragm, an electron optical pre-concentrating system adapted to produce a first focus of said cathode ray in the aperture of said first diaphragm, said preconcentrating system consisting of said first diaphragm and two further apertured diaphragms mounted between said first diaphragm and said control electrode, the intermediate of said three diaphragms having a smaller distance from said first diaphragm 10 than from the third of said diaphragms, the apertures of said three diaphragms having decreasing diameters in the direction from said cathode, the size of the aperture of said first diaphragm being approximately equal to one fifth of the size of the active emissive surface of 15 said cathode, said first diaphragm being formed by a solid plano-parallel metallic disc having a conical recess at its centre, the smaller end of said recess being covered by a thin sheet of platinum having a central opening.

10 9. A cathode ray tube comprising means in-

cluding a cathode for producing a cathode ray, an intensity control electrode mounted in front of the emissive surface of said cathode, a first apertured diaphragm, an electron optical pre-concentrating system adapted to produce a first focus of said cathode ray in the aperture of said first diaphragm, said preconcentrating system consisting of said first diaphragm and two further apertured diaphragms mounted between said first diaphragm and said control electrode, 10 the apertures of said three diaphragms having decreasing diameters in the direction from said cathode, the size of the aperture of said first diaphragm being approximately equal to one fifth of the size of the active emissive surface of said 15 cathode, the diameter of the aperture of the intermediate of said three diaphragms being approximately equal to the distance of said intermediate diaphragm from said first diaphragm, both being approximately equal to 1 mm.
